DESIGN FOR A COOK STOVE

Boyd W. Tullis, Wichita, Kans., assignor to Coleman Lamp & Stove Company, Wichita, Kans., a corporation

Application July 25, 1938, Serial No. 78,707

Term of patent 3½ years

To all whom it may concern:

Be it known that I, Boyd W. Tullis, a citizen of the United States, residing at Wichita, in the county of Sedgwick and State of Kansas, have invented a new, original, and ornamental Design for a Cook Stove, of which the following is a specification, reference being had to the accompanying drawing, forming part thereof.

The top of the stove including the grates, and the border around the oven door are shaded to represent a color in contrast to the body of the cook stove.

I claim:

The ornamental design for a cook stove, as shown and described.

BOYD W. TULLIS.
